CLARENCE I. J. BARKER, OF NEOSHO, MISSOURI.

COMBINATION CHEST AND TABLE.

Application filed March 18, 1924. Serial No. 700,131.

To all whom it may concern:

Be it known that I, CLARENCE I. J. BARKER, a citizen of the United States, residing at Neosho, in the county of Newton and State of Missouri, have invented new and useful Improvements in Combination Chests and Tables, of which the following is a specification.

This invention relates to combination 10 chests and tables.

The object is to provide an article of furniture having two distinct uses, and which may be quickly converted into a complete chest for holding articles of food, liquids, etc., to be used by tourists, motorists or others, and which may be as readily changed into a complete table for serving lunches or for other purposes.

Another object is to provide a device of 20 this character which, when folded and locked into the form of a chest, may receive the table legs therein in a minimum amount of space so as to allow ample room for the storage of foods, etc., the said chest being 25 normally open at the top for the reception of the foods or liquids, and adapted to be closed by a separate cover in the form of a tray, which may be also used for serving purposes after the contents of the chest have 30 been removed and the device converted into a table.

A final object is to provide a combination chest and table which may be cheaply manufactured and sold at a low cost, having few 35 parts to get out of order, and which may be converted from one form to the other by a very simple operation and which, in either form, has no appearance of being of a convertible character.

A full and complete understanding of the 40 invention may be obtained from a consideration of the following detailed description, taken in connection with the accompanying drawings forming a part of this specification, 45 it being understood that while the drawings show a practical form of the invention, the latter is not to be confined to strict conformity with the showing thereof, but may be changed or modified, so long as 50 such changes or modifications mark no material departure from the salient features of the invention, as specifically pointed out in the appended claims.

In the drawings, in which similar refer-

ence characters designate corresponding 55 parts throughout the several figures:

Figure 1 is a perspective view of the device in the form of a chest.

Figure 2 is a top plan view of the same, 60 the cover or tray being removed and showing the table legs stowed in the bottom thereof.

Figure 3 is a central, vertical sectional view, taken on the line 3—3 of Figure 2, 65 with the cover or tray in place.

Figure 4 is a transverse section taken on the line 4—4 of Figure 2, also showing the cover or tray in position.

Figure 5 is a detail perspective view of 70 the chest cover ready for use as a serving tray.

Figure 6 is an inverted plan view of the 75 chest sections opened and locked together to form a table top and having the supporting legs in active position.

Figure 7 is a detail view of one of the 75 fasteners or reinforcements for the mitered corners of the table top sections.

Figure 8 is a perspective view, drawn on a reduced scale, of the convertible device 80 set up as a table.

The improved combination chest and table of the present invention is primarily designed to fulfill the wants of automobileists or tourists and is well adapted to be 85 carried, while in the form of a chest, on the running board of automobiles, the two sections constituting the table top, and the sides of said chest being so formed and hinged together as to provide an entirely open top 90 into which fragile foods, such as pies, pastries, cakes or other foods or dishes, as well as liquids or liquid containers may be readily placed and safely carried and protected from dust, dirt, or the weather while 95 in transit, the said chest and cover being adapted to be strapped together and held in position on the machine. By removing the straps and the cover, the chest, being securely locked in form, may be carried with 100 the contents to the desired location and the foods removed therefrom as from an ordinary chest, without danger of spilling or breaking the same, which is not the case in other foldable or convertible chests which close up in the manner of a suit case and wherein it is necessary to carry all the contents in an inverted or semi-inverted posi-

tion, thus spilling and damaging the same. By releasing certain locking means, after the contents of the chest have been removed, the two sections of the chest may be swung about their hinges, and be arranged into horizontal alinement with each other and again locked to form a table top having all the appearances of an ordinary table top, after which the four legs, previously carried in the chest, may be inserted and the table turned to standing position thereon.

Each section or half of the chest and table top comprises a relatively wide panel 1 which may be formed of one or more boards, preferably of hard wood, having their ends and outer edges preferably rounded as shown, and these panels form the vertical side wall of the chest and also the top of the table.

20 Adjacent to the outer rounded edges of the panels 1, there are secured preferably by concealed nails or screws, longitudinally disposed strips or rails 2, likewise formed of hard wood and extending perpendicularly to said panels. The rails 2 have their outer ends mitered and joined to the correspondingly mitered ends of adjacent end rails 3 arranged at right angles to the same and likewise perpendicular to the said panel 1. 25 The abutting, mitered ends of the rails 2 and 3 are provided with longitudinally disposed grooves for the reception of the angular arms 4 of a corner fastening device, as shown in detail in Figure 7. The fastening device is provided with terminal, angular prongs 5 which are adapted to be driven into the rails so that the angular fastener serves to hold the said rails together with the arms 4 flush with the outer exposed edge of the rails.

40 The ends of the relatively short end rails 3 opposite to the mitered joints are cut off square, and in alinement with the inner edges of the panels 1 which are also square, and suitable hinge elements 6 are screwed or otherwise secured to the free edges of said rails 3 in a manner to permit the sections to be swung so that the long, free edges of the end rails 3 may abut, when the device is in the form of a chest (as shown in Figures 2, 3 and 4), or to permit the said sections to be swung so that the short, free edges of the end rails may abut, as when the device is in the form of a table (as shown in Figures 5 and 8). One of the hinge elements is preferably countersunk, as shown, while the other is attached to the surface of the adjacent rail 3, and the eyes of the hinges extend above the plane of the end rails 3 when in chest form, as shown in Figure 4.

60 The free, longitudinal edges of the panels 1 are provided with reinforcing battens or strips 7, each having one edge flush therewith and the end rails 3 are mortised for the reception of the ends of said strips, which

latter are in abutting relation when the device is in the form of a table, and serve to stiffen and strengthen the same as well as when the said panels constitute the long sides of the chest.

70 Cleats 8 are nailed or otherwise secured to the inner faces of the rails 2 and 3, said cleats being arranged transversely of said rails and in spaced relation to the mitered joints thereof, to provide corner sockets 9 into which are adapted to be fitted the upper, relatively large ends of tapered legs 10, as clearly shown in Figure 5.

80 The cleats 8 attached to the end rails 3 of one panel 1 are provided with swingable hooks 11, while the corresponding cleats 8 of the opposite panel 1 are provided with headed pins 12 for receiving said hooks 11 when the device is in the form of a chest, as shown in Figure 4, said hooks serving to hold the two sections together with the free edges of the end rails 3 in abutting relation.

85 One of the reinforcing strips 7 is provided with a swingable hook 13 which is adapted to engage a headed pin 14 carried by the other reinforcing strip 7 when the device is straightened out with the panels in horizontal alinement to form a table top (Fig. 5).

90 A cover 15, formed of suitable sheet metal of a size to fit down over the open end of the chest, is provided with marginal flanges 16 to form a tight joint around the same for the purpose of excluding dirt, dust, or moisture, and the said cover is further provided with bosses 17 struck up from the metal and adapted to accommodate the upwardly projecting hinge eyes, as shown in Figure 4. The cover 15, in addition, forms a convenient tray, when removed from the chest, for holding articles of food or for serving the same.

95 When the chest is packed and with the cover or tray 15 in position thereon, the whole may be held by suitable straps 18, as indicated in Figure 1 of the drawing, and carried on the running board of a motor car or otherwise.

100 By reason of the tapering form of the legs 10, the same may be placed within the chest, in alternately reversed position, as shown in Figure 2, and occupy a minimum amount of space therein, the faces thereof being substantially flush with the faces of the cleats 8, so that dishes or articles of food may be placed upon the same with safety, the said legs being of a length to fit between said cleats.

105 The two sections of the device, when arranged as a chest, provide an open top to the latter the full extent of the internal area of the same, and it is not necessary to tilt or invert the sections in order to gain access to the interior, as is the case in similar devices which open in the manner of a suitcase.

After the straps 18 have been released and the cover 15 removed, the legs may be taken out and the hooks or latches 11 detached from the pins 12, when the two sections 5 may be swung about their hinges and the hook 13 engaged with the pin 14 to form the table top, after which the legs may be installed in position and the whole inverted to stand on the legs in the ordinary manner. 10 From the foregoing it will be seen that a simple, cheaply manufactured, and easily operated combination chest and table has been provided which is especially well adapted for use by motorists and tourists, 15 the same being compact, strong and durable.

What is claimed is:—

1. A combined chest and table comprising two substantially equal rectangular sections each having a longitudinal rail and two 20 transverse end rails, the free corners of each pair of end rails on one section being hinged to the corresponding corners of the other section, said sections being swingable on the hinges into abutting relation to form an open-topped chest or swingable to lie in the same plane to form a table top, and means for holding the sections in either 25 position.

2. A combined chest and table comprising two substantially equal, elongated rectangular sections, each section comprising a panel having perpendicular rails along one long margin and short, perpendicular end rails across the ends, means for securing 30 the three rails of each section together and to the panel, the end rails of the opposite sections being hinged together at their inner 35 corners so as to form the end walls of an open-topped chest with the long rails forming the bottom wall of said chest when the 40 sections are swung with the free edges of the rails abutting each other, means for locking the sections together, table leg sockets formed in each corner of the rails, table 45 legs stowable within the bottom of the chest,

and a cover adapted to fit over the open top of the chest.

3. A combined chest and table comprising two substantially equal rectangular sections each having a longitudinal rail and two 50 transverse end rails, the free corners of each pair of end rails on one section being hinged to the corresponding corners of the other section, said sections being swingable on the 55 hinges into abutting relation to form an open-topped chest or swingable to lie in the same plane to form a table top, sockets formed at the angles of the sets of rails, table legs stowable within the bottom of the sections when in chest form and adapted to have 60 their upper ends set into the sockets when the sections form a table top, means for locking the sections together as a chest, and separate means for locking said sections together as a table top. 65

4. A combined chest and table comprising two substantially equal rectangular sections, each consisting of a panel, a longitudinal side rail and two end rails, the side and end rails being secured to each other and 70 to the panels, means for hinging the end rails of each section to the others at their free inner corners, whereby the two sections are hinged together with the end rails forming the end walls, the panels forming the 75 side walls and the side rails providing the bottom wall of an open top chest, means for holding the sections in this position, the sections being adapted to be swung so that the two panels may be arranged in alignment and form the top of a table, means for holding the sections in the second position, and a cover for the open top of the 80 chest, said cover when removed serving as a tray. 85

In testimony that I claim the foregoing as my own, I have hereto affixed my signature.

CLARENCE I. J. BARKER
